UNITED STATES PATENT OFFICE.

CAROLINE M. STRONG, OF SPRINGFIELD, MASSACHUSETTS.

COMBINED BUSTLE AND HIP-PAD.

SPECIFICATION forming part of Letters Patent No. 286,562, dated October 9, 1883.

Application filed May 12, 1883. (No model.)

To all whom it may concern:

Be it known that I, CAROLINE M. STRONG, a citizen of the United States, residing at Springfield, in the county of Hampden and State of Massachusetts, have invented new and useful Improvements in a Combined Bustle and Hip-Pad, of which the following is a specification.

This invention relates to the construction of an improved bustle and hip-pad combined; and it consists in a hip-pad made as hereinafter described. The skirt of the hip-pad is secured to a waistband and reaches nearly around a person, and has a bustle secured thereto, at the rear, at the junction of said skirt with said waistband.

In the drawings forming part of this specification, Figure 1 is a front view of a corset having secured around it, in the position in which it is worn, a combined bustle and hip-pad constructed according to my invention. Fig. 2 is a rear view, showing the lower portion of the parts shown in Fig. 1. Fig. 3 is a transverse section.

In the drawings, A is the waistband, B is the hip-pad, and D is the bustle. e indicates the curled hair in the hip-pad and in the bustle.

The hip-pad parts—that is to say, the outer and inner short skirt-shaped pieces—are made from any suitable cloth, being adapted by their form to descend and surround, nearly, the person of the wearer, substantially as shown, so as to nearly cover the hips, or quite so, if desired. The said hip-pad parts v v are sewed by their upper edges to the waistband A, (the latter being provided with the usual buckle or other suitable fastening device,) and between them is interposed a filling, preferably of curled hair, which constitutes a light and very elastic filling, which is unobjectionable respecting ventilation; and said parts v v and curled hair e are united into said pad by sewing through them at intervals, as shown, and by uniting the lower edges of said parts v v.

The bustle D is made of the usual crescent shape, and is, like the hip-pad B, filled with curled hair, and is attached to the hip-pad at the point of its junction with the waistband A.

The above-described construction of a combined hip-pad and bustle provides a light and easily-compressible article of wearing-apparel, but possessing every requisite for imparting to the form of the wearer the desired fullness just below the waist and around the hips; and the bustle D, constituting a part of the combined article, and also filled with said curled hair e, serves the usual purpose of said part. The two together conduce to produce a more graceful form in or impart to the overlying skirts of the wearer a more pleasing line of fullness than when the bustle is used separately.

What I claim as my invention is—

The combined bustle and hip-pad described, consisting of the waistband A, having secured thereto the hip-pad B, the padded portion of which is adapted to extend above the hips and well forward around the person of the wearer, as shown, and the bustle D, also secured to the waistband, so as to rest above and upon the rear portion of the hip-pad, all substantially as described, and for the purpose set forth.

CAROLINE M. STRONG.
